UNITED STATES PATENT OFFICE

152,757

DESIGN FOR A TAXICAB CRUISING LIGHT

Francis Joseph Toomey, Huntsville, Ohio, assignor to Edith G. Toomey, Huntsville, Ohio

Application December 15, 1947, Serial No. 143,143

Term of patent 7 years

(Cl. D48—32)

To all whom it may concern:

Be it known that I, Francis Joseph Toomey, a citizen of the United States and a resident of Huntsville, in the county of Logan and State of Ohio, have invented a new, original, and ornamental Design, for a Taxicab Cruising Light, of which the following is the specification, forming part thereof reference being had to the accompanying drawings, wherein:

I claim:

The ornamental design for a taxicab cruising light, substantially as shown.

FRANCIS JOSEPH TOOMEY.
